UNITED STATES PATENT OFFICE.

BENJAMIN JAMES HALL, OF EASTCOTE, ENGLAND.

MACHINE FOR SENSITIZING PAPERS AND OTHER FABRICS.

Application filed March 3, 1922. Serial No. 540,823.

To all whom it may concern:

Be it known that I, BENJAMIN JAMES HALL, a subject of the King of Great Britain, residing at Fieldend, Eastcote, in the county of Middlesex, England, have invented new and useful Improvements in Machines for Sensitizing Papers and Other Fabrics, of which the following is a specification.

10 This invention refers to machines for sensitizing papers and other fabrics, and has for its object to economize floor space, simplify the working and increase the output.

In the coating of blue print paper, after the application and distribution of the sensitizer, the material has to be dried, and this is at present accomplished by passing the material through a chamber containing hot air.

20 The sensitizing process is rapid, but the process of drying by hot air is necessarily slow, and in order to obtain an adequate output the drying chamber has to be of considerable size involving large floor space or 25 other inconveniences.

Now, according to my invention, I use a hollow body or bodies, which I term the radiator, heated internally by hot water or steam or gas or electricity. Or heated on 30 one surface by gas, electricity or the like, in which case the radiator may be solid.

The outer surface of the radiator is preferably convex and presents a smooth surface over which the coated paper is drawn and 35 dried, the uncoated side of the paper being in contact with the radiator.

The radiator may be constructed of any suitable material or materials and waste 40 radiation of heat prevented by the application of non-heat conducting material where possible.

In order that the invention may be clearly understood I have appended the accompanying drawings.

45 Fig. 1 is a side elevation of the machine constructed according to my invention.

Fig. 2 is a back elevation.

A represents the hollow body which may be heated by hot water, steam, gas or electricity and which I term the radiator, B the reel of paper, D the trough or bath containing the coating liquid, E the coating roller which revolves in the bath D, e¹ the guide rollers which guide the paper over the roller E, F the draining board which drains the superfluous liquid from the paper back into

the trough D, e² the guide rollers which guide the paper over the radiator A, the uncoated side of the paper being in contact with said radiator, H the scraper which 60 scrapes the coated side of the paper as it passes over guide rollers e², e³ another guide roller which guides the paper, as it leaves the radiator, to the take off rollers J, and K the board or table on to which the paper is 65 discharged as it leaves the take off rollers.

As the paper, shown in dotted lines Fig. 1, is drawn from the reel B it first passes under one of the guide rollers e¹, then over the coating roller E and under the other 70 guide roller e¹ and from thence over guide rollers e², the coated surface of the paper at this point being scraped by the scraper H or scrapers—as it passes over these latter rollers. The paper now passes in contact 75 with the one surface of radiator A and then around roller e⁴ and in contact with a second surface of radiator A and from thence under guide roller e³ to the take off rollers J.

The hollow body A is a vertical heating 80 chamber having plane surfaces at its front and rear sides which are arranged at an acute angle to each other, with the apex of the chamber at its top, and the guide roller e⁴ arranged above its top. The moist material rests against the front and rear sides of the chamber, and these sides may be 85 covered with any approved protecting material to prevent injury to the moist material by direct contact with the sides of 90 the chamber.

It will be seen by constructing a machine in the manner herein set forth that the floor space occupied to accomplish both the coating and drying operations is little if any 95 extra to the floor space required for a machine in which the coating operation only is performed and that as a considerable area of heating surface is provided over which the paper has to travel the drying process 100 is completed without delaying the coating operation.

What I claim as my invention and desire to secure by Letters Patent is:—

1. In a sensitizing machine, a coating device for applying fluid to the material, a vertical heating chamber having its front and rear sides arranged at an acute angle to each other, a guide roller arranged above the apex of the chamber, front and rear 105 guide rollers arranged adjacent to the lower part of the chamber, and means for drawing 110

the material to be sensitized through the coating device and over the said guide rollers so that it is dried by the heated front and rear sides of the said chamber.

5 2. A sensitizing machine as set forth in claim 1, provided with two front guide rollers arranged one above the other, and means for scraping the coated surface of the material in its passage between the said 10 front guide rollers.

In testimony whereof I have signed my name to this specification in the presence of two subscribing witnesses.

BENJAMIN JAMES HALL.
